UNITED STATES PATENT OFFICE.

MENZO M. BENSTER, OF GETTYSBURG, SOUTH DAKOTA.

FLYING-MACHINE.

1,027,372.

Specification of Letters Patent.

Patented May 21, 1912.

Application filed March 5, 1910. Serial No. 547,491.

To all whom it may concern:

Be it known that I, MENZO M. BENSTER, a citizen of the United States, and a resident of Gettysburg, in the county of Potter and State of South Dakota, have invented a new and Improved Flying-Machine, of which the following is a full, clear, and exact description.

This invention relates to flying machines, and particularly to that type known as "heavier-than-air" or "aeroplane."

An object of this invention is to provide a flying machine which will be simple in construction, inexpensive to manufacture, simple and efficient in its operation, and easily directed.

A further object of this invention is to provide a flying machine with a plurality of wings adapted to be swung through the air, to simultaneously raise and propel the machine.

A still further object of this invention is to provide a flying machine with propelling means, and with mechanism for driving the same, said mechanism having an auxiliary driving connection whereby an accidental breakage may happen without destroying the flight of the machine.

These and further objects, together with the construction and combination of parts, will be more fully described hereinafter and particularly set forth in the claims.

Reference is to be had to the accompanying drawings forming a part of this specification, in which similar characters of reference indicate corresponding parts in all the views, and in which—

Figure 1 is a side view in elevation, with the outer disks removed for the purpose of disclosing the underlying parts; Fig. 2 is a top plan view, with parts broken away to show the underlying structure; Fig. 3 is a front end view in elevation; Fig. 4 is a vertical transverse section showing the mechanism for connecting the driving gearing to the disks; Fig. 5 is a vertical section illustrating the clutch for connecting the propeller with the driving mechanism; and Fig. 6 is a detail view, partly in section, showing the means for throwing in the auxiliary drive.

Referring more particularly to the separate parts of the device, 1 indicates the frame of the flying machine, which may be made of any suitable light material, such as bamboo, hollow aluminum rods, or the like,

and formed in a manner to provide a strong and substantially rigid structure. The frame 1 is suitably supported on a plurality of rollers 2 and 2', the utility of which will be described hereinafter. Secured adjacent the top of the frame 1, intermediate the sides thereof, there is provided a suitable supporting plane 3, which is preferably arcuate in form, and may be made of any suitable light material, such as Japanese silk, oiled linen, or the like, stretched over a suitable framework. At each end of the plane 3, representing the front and rear of the machine, there are provided hoods 5 and 6, which are adapted to aid in the up and down directing of the machine as a whole in its travel through the air, and may be made of the same material as the plane 3. These hoods 5 and 6 are pivotally connected to the frame, so as to swing from the full-line position indicated in Fig. 1 to the dotted-line position indicated in the same figure. In order to produce this tilting or swinging motion, the hoods 5 and 6 are provided with arms 7 and 8, which are pivotally connected to rods 9 and 10. The rods 9 and 10 are connected at their opposite ends to levers 11 and 12, pivotally secured in any well known manner to the frame 1, by which the rods 9 and 10 and the hoods 5 and 6 are operated. Adjacent the bottom of the frame 1, subjacent the hoods 5 and 6 at each end of the flying machine, there are provided additional hoods 13 and 14, which are similar to the hoods 5 and 6, and have arms 15 and 16 connected thereto, whereby they are operated. The arms 15 and 16 are pivotally connected to rods 17 and 18, which are also pivotally connected at their opposite ends to levers 19 and 20. It will thus be seen that by this means each of the hoods 5 and 6, 13 and 14 are independently operated by separate levers, so that the up and down direction of the machine as a whole can be readily controlled to a nicety.

In order to control the motion of the machine toward the right and left, there is provided a vertical rudder 21, which is operated by a lever 22, connected thereto by means of a rod 23 and an arm 24.

In order to propel the flying machine in a forward direction, there is provided a propeller 25, which may be of any suitable form, and is secured to a propeller shaft 26, rotatably supported in bearings on the frame 1. The propeller shaft 26 (as is more clearly

illustrated in Fig. 5) is provided with clutch members 27, which are adapted to be engaged by pivoted clutch members 28 on a sleeve shaft 29. The opposite ends of the 5 clutch members 28 are adapted to be forced outwardly in order that the clutch members 28 may engage the clutch members 27, by means of a cone 30, which is splined on the sleeve shaft 29. The cone 30 is operated by 10 a wheel 31, which has a screw-threaded engagement 32 with a stationary support 33. By this means, the propeller shaft 26 can be clutched at will to the sleeve shaft 29, which is connected to the power motor in a manner 15 to be described. The power sleeve shaft 29 is rotatably supported in suitable bearings in the frame 1, and has secured at its opposite end a bevel gear 34. A bevel gear 35 is formed on a driving member 36, loosely mounted on 20 a shaft 54, and is also provided with a sprocket wheel 37, whereby the driving member 36 is connected to a suitable motor 38, preferably in the form of a gasoline engine, by means of a chain 39 and a sprocket 25 wheel 40.

In case the chain 39 should break, there is provided an auxiliary driving connection between the member 36 and the motor 38. This consists of bevel gears 41 and 42 connected respectively to the driving member 36 and the power shaft of the engine 38, and a shaft 43 provided at each end with bevel gears 44 and 45, which are adapted to mesh with the bevel gears 41 and 42. The mechanism for throwing the bevel gears 44 and 45 into mesh with the bevel gears 41 and 42 is more clearly shown in Fig. 6. The shaft 43 is supported at its lower end on a member 46, which is adjustably secured in a support 47. The shaft 43 is provided with a collar 48, which is engaged by a forked arm 49 of a bell crank lever 50, which is pivotally supported on the support 47. The fork of the arm 49 engages on each side of the shaft 43, and is adapted to force it upward by engaging with the collar 48. It will be seen that the lever 50 can be readily manipulated to force the gears 44 and 45 into engagement with the gears 41 and 42. It is to be noted that the member 46 is screw-threaded and engages a corresponding screw-threaded opening in the support 47, and is further provided with a handle 51, whereby this member 46 may be screwed into the support 47 to hold the shaft 43 in its raised position, with the gears 44 and 45 in engagement with the gears 41 and 42.

For the purpose of raising the machine bodily, additional means, in the shape of 60 wings, is used. Considering this means, the shaft 54 has secured at its outer end a disk or fly-wheel 55. On the opposite end of the shaft 54, there is provided a sleeve shaft 56, which also has secured on its outer end a fly-wheel or disk 57. The shafts 54 and 56 have

splined thereon clutches 58 and 59, which are adapted to be forced into engagement with clutch faces 60 and 61 on the drive member 36, by means of springs 62 and 63. The clutches 58 and 59 can be thrown out of engagement with the clutch faces 60 and 61 by means of levers 64 and 65, pivotally connected thereto in any well known manner. By this means, it will be seen that the shafts 54 and 56 can be clutched to the member 36 in any adjusted position relative to each other. At the rear end of the frame 1, there is provided a shaft 66, which is journaled in the frame 1 in any well known manner, and is provided at its outer end with disks 67 and 68, which are similar to the disks 55 and 57, and are connected thereto by means of rods 69 and 70, so that they are driven in unison therewith. All of the disks 55, 57, 67 and 68 are provided with slots 71, extending through which in such a manner that they may be adjusted toward and from the center of the disks, there are provided sleeve shafts 72. Secured to the sleeve shafts 72, there are arch frames 74, on which is supported the fabric for suitable wings 75, which preferably extend downwardly at their outer ends beyond the frame 74, as indicated at 76. It will thus be seen that as the disks or fly-wheels are rotated, the wings will be swung up and down in a circular path, so as to raise the machine, and also propel it through the air.

In order to aid the propulsion due to the wings, there are provided a plurality of 100 shafts 77, which, in the case of the end shafts, extend through the sleeve shafts 72. The portions of the shafts 77 which extend beneath the wings 75 are provided with blades 78 of a form adapted to swing 105 in the arch of the wings. The blades 78 are so arranged that in the forward motion of the wings, they will extend substantially horizontally, and will then be tilted to a vertical position, so that, on the rearward motion of the wings, they will exert a backward force on the air, tending to propel the machine forward. For this purpose, the inner ends of the shafts 77 are provided with gears 79, which are of the proper dimensions to be rotated a quarter of a revolution when they come in contact with stationary racks 80 and 81 suitably secured to the frame 1. By this means, the blades 78 will be swung from a horizontal position at the end of the forward motion of the wings 75 to a vertical position, so as to remain in this position during the rearward movement of the wings, and will be revolved a quarter of a revolution at the end of the rearward motion by the racks 81, so as to be again in a horizontal position, offering little or no resistance to the forward motion thereof. The blades 78 are prevented from revolving backward when exerting a propelling force 110 115 120 125 130

on the air, by means of spring catches 82, which are of such a nature as to permit the forward motion of the blades and yet prevent their rearward motion.

5 While the propeller 25 might be utilized to run the flying machine along the ground in order to obtain sufficient momentum to raise the machine from the ground, I prefer to drive one of the supporting wheels 10 2' from the motor 38. For this purpose, there is provided on the side of the wheel 2' a pulley 83, which is driven from a corresponding pulley 84 on the engine shaft, by means of any suitable flexible connection 15 85, such as a rope, belt, chain, or the like. It is undesirable that the wheel 2' should be driven when the machine is in the air, and the flexible connection 85 is therefore made of such a length that it will be somewhat 20 slack when passing loosely over the pulleys 83 and 84. In order to tighten the flexible connection 85 and make the drive positive between the pulley 84 and the pulley 83, I provide a roller 86, which is rotatably supported on a lever 87, pivotally connected to the frame in any well known manner. The operator can thus, by manipulating the lever 87, control the feed of driving of the wheel 2' from the engine shaft from no 30 speed up to the maximum speed of the engine.

In order that the flying machine may be properly guided when on the ground, so as to turn to the right or to the left, the front 35 wheel 2 is swivelly connected to the frame, and is provided with an arm 88, shown in dotted in Fig. 3, which is adapted to be operated by a lever 89, which extends rearwardly to a position adjacent the other 40 levers on the machine, where it can be readily manipulated by the operator.

The operation of the device will be readily understood when taken in connection with the above description. When it is desired 45 to use the machine, the wheel 2' can be driven, giving an initial propulsion to the machine, thereby traversing the machine along the ground. When a sufficient momentum has been obtained, the machine can 50 be raised from the ground by tilting both of the forward planes or hoods 5 and 13 upwardly, thereby lifting the front end of the machine. If sufficient force is not thus obtained to lift the machine from the ground, 55 the wings 75 can be actuated by throwing in the clutches 58 and 59. The clutches may be thrown in simultaneously, so as to have both of the wings 75 operated together, or one may be thrown in first and the other 60 thrown in later, so as to have the wings reciprocating in opposite directions. In whatever way the wings are connected up to the driving mechanism, however, the blades 78 will be actuated by means of the gears 79 65 and the racks 80 and 81, to automatically

tilt to a horizontal position on the forward motion of the wings 75, and automatically tilt back to a vertical position just before the rearward motion of the wings 75, thereby causing the blades to offer the least resistance to the forward motion of the machine, and yet propelling the machine forwardly on their rearward stroke. The stroke of the wings 75 can be increased or decreased by adjusting the sleeve shafts 72 in 70 the slots 71. When once in the air, the up and down direction of the machine can be controlled by the hoods 5, 6, 13 and 14, by means of the levers connected thereto. The horizontal direction can also be controlled 80 by the rudder 21. If, by any chance, the drive chain 39 should break, the auxiliary driving mechanism, consisting of the shaft 43 and the gears 44 and 45, can be thrown into operation by means of the lever 53, thus 85 preventing the machine from hurtling to the ground. However, even if the driving mechanism should break, the planes and wings being arcuate in form, will provide 90 efficient parachutes to prevent the sudden fall of the flying machine.

While I have shown one form of my invention, I do not wish to be limited to the specific details of the form shown, but desire to be protected in various changes, alterations and modifications which I may make within the scope of the appended claims.

Having thus described my invention, I claim as new and desire to secure by Letters Patent:—

1. In a flying machine, the combination with a frame, of a supporting plane on said frame, a plurality of wings connected to said frame on each side thereof and having 105 a supporting surface, means for operating said wings, and blades adjustably connected to said wings and independent of said supporting surface.

2. In a flying machine, the combination with a supporting frame, of a supporting plane on said frame, a plurality of wings connected to said frame on each side thereof and having a supporting surface, means for operating said wings, blades connected 110 to said wings and independent of said supporting surface, and means for positively shifting said blades from a horizontal to a vertical position during the motion of said wings.

3. In a flying machine, the combination with a frame, of a motor on said frame, a pair of disks connected to said frame and operatively connected with said motor, a pair of disks operatively connected to said first-mentioned disks, and wings adjustably connected to said disks.

4. In a flying machine, the combination with a frame, of a shaft in said frame, a disk connected to said shaft, a sleeve shaft 130

connected to said first-mentioned shaft, a disk connected to said sleeve shaft, wings connected to said disks and adapted to be operated thereby, and means for operating 5 said shafts.

5. In a flying machine, the combination with a frame, of a shaft connected to said frame, a sleeve shaft connected to said first-mentioned shaft, a motor for driving said 10 shafts, and means for independently connecting said shafts to said motor, disks connected to said shafts and adapted to be driven thereby, and wings connected to said disks and adapted to be operated thereby.

15. 6. In a flying machine, the combination with a frame, of a shaft rotatably supported in said frame, a driving member rotatably supported on said shaft and having clutch faces thereon, a clutch on said shaft, 20 means for forcing said clutch into engagement with one of said clutch faces, a shaft connected to said first-mentioned shaft, means for connecting said last-mentioned clutch with the other of said clutch faces, 25 disks secured to said shaft, and wings connected to said disks and adapted to be driven thereby.

7. In a flying machine, the combination with a frame, of a pair of wings connected to 30 said frame on opposite sides thereof, blades rotatably connected to said wings, gears connected to said blades, and racks on said frame adapted to rotate said gears so as to swing said blades intermittently through 35 angles of 90 degrees.

8. In a flying machine, the combination with a frame, of wheels for rotatably sup-

porting said frame on the ground, a supporting plane on said frame, disks rotatably connected to said frame, wings connected 40 to said disks and adapted to be operated thereby, blades rotatably supported by said wings, means for operating said disks, and means for positively rotating said blades to swing from a horizontal to a vertical position during the motion of said wings. 45

9. In a flying machine, the combination with a frame, of wings for raising said machine in the air, pivotally connected to said frame so as to swing or beat, and means for 50 adjustably connecting said wings at variable distances from their pivotal connection with said frame, so that the magnitude of the swing or beat of said wings can be varied. 55

10. In a flying machine, the combination with a frame, of a variety of wings for raising said machine in the air movably mounted on said frame to swing or beat, and adjustable connections between each of said 60 wings and said frame, whereby said wings can be moved to variable distances with respect to their point of connection with said frame, and can be adjusted to maintain different relative positions with respect to each 65 other.

In testimony whereof I have signed my name to this specification in the presence of two subscribing witnesses.

MENZO M. BENSTER.
